HOISTING MECHANISM

Robert C. Osgood, Claremont, N. H., assignor to
 Sullivan Machinery Company, a corporation of
 Massachusetts

Application October 27, 1936, Serial No. 107,855

9 Claims. (Cl. 254—187)

This invention relates to hoisting mechanisms, and more particularly to improvements in hoisting mechanisms or winches especially designed for use with life boat launching apparatus.

In conventional forms of life boat launching apparatus, life boats are usually launched, or hoisted after launching, by means of davits mounted on the deck of the ship and embodying swinging arms or booms carrying pulleys around which the cables for lowering or hoisting the life boats pass, these cables extending about suitable guide pulleys on the deck to a double drum hoist or winch located near one davit at one end of a life boat or between the adjacent ends of a pair of life boats. When it is desired to launch the life boats, the davit booms are swung outwardly by conventional means so that their outer extremities project outwardly over the side of the ship so as to suspend the life boats supported thereby out over the side of the ship. The hoist drums are then operated to effect unwinding of the cables to effect lowering of the life boats. Usually, suitable means is provided for braking the drums and for preventing an excessive unwinding speed of the cables. During hoisting of the life boats, the drums are operated by a motor or hand cranks for effecting winding in of the cables, the drum braking means usually releasing automatically, or being automatically disconnected from the drums, when the drums are rotated in cable winding direction. In known forms of launching apparatus for launching nested life boats, manual means is employed for effecting rapid winding in of the cables by hand when the drums are relieved of their load, this hand operating means being connected to the drums independently of most or all of the drum driving gearing embodied in the motor or hand crank operated winding means, so that the cables may be rapidly wound in by hand for connection to another life boat to be lowered.

An object of this invention is to provide an improved hoisting mechanism or winch. Another object is to provide an improved hoist or winch especially designed for use with the davits of a life boat launching apparatus, whereby launching of the boat is effected in an improved manner. A further object is to provide an improved hoist or winch having embodied therein improved drum braking means for controlling unwinding of the cables on the drums and improved automatic "free wheeling" clutch means for effecting disconnection of the braking means from the drums during rotation of the latter in cable winding direction, the braking means having associated therewith automatic centrifugally operated braking means for automatically preventing an excessive rate of rotation of the drums in unwinding direction during the lowering of the load. Still another object is to provide an improved interlocking means for the drum drive

control clutch and drum brake so that when the drums are connected in driving relation with the driving motor, release of the brake to permit rotation of the drums in unwinding direction is precluded, it being necessary to release the clutch prior to brake release. Still another object is to provide an improved means for manually rapidly rotating the drums in winding direction, when the drums are disconnected from the motor operated drum driving gearing, so that the cables may be rapidly wound in by hand. Other objects and advantages of the invention will, however, hereinafter more fully appear.

In the accompanying drawings there is shown for purposes of illustration one form which the invention may assume in practice.

In these drawings—

Fig. 1 is a front elevational view of the illustrative form of the improved hoisting mechanism.

Fig. 2 is an elevational view of the hoisting mechanism shown in Fig. 1, as viewed from one end of the mechanism.

Fig. 3 is an elevational view of the improved hoisting mechanism, as viewed from the opposite end of the mechanism.

Fig. 4 is a developed vertical sectional view taken substantially on line 4—4 of Fig. 2.

Fig. 5 is a detail vertical sectional view taken on line 5—5 of Fig. 4.

Fig. 6 is a detail vertical sectional view taken on line 6—6 of Fig. 4.

Fig. 7 is a detail vertical sectional view taken on line 7—7 of Fig. 4.

In this illustrative embodiment of the invention there is shown a hoisting mechanism or winch, generally designated 1, especially designed for use with a life boat launching apparatus of any conventional type, so that lowering of the life boats may be maintained at all times under control. This improved hoist or winch, in this instance, is designed for the launching of a pair of life boats and comprises a frame 2 adapted to be mounted, in the usual manner, on the deck of a ship, preferably in adjacency to the davit mechanism, and journaled on this frame are pairs of winding drums 3, 3 and 4, 4, herein arranged on parallel axes, and the drums of each pair being integrally united for rotation in unison and having wound thereon cables 5, 5 and 6, 6. These cables are adapted to be passed around suitably located sheaves on the ship deck and davit mechanism, so that the cables may be operated to lower or raise the life boats suspended by the davits over the side of the ship. As the davits, guide pulleys and other mechanism of the launching apparatus are of a conventional form, further description thereof is considered unnecessary.

Again referring to the specific winch or hoist structure, it will be noted that the pairs of drums 3, 3 and 4, 4 are journaled on parallel horizontal

cross shafts 7, in turn journaled in roller bearings 8 supported within the sides of the hoist frame. Mounted on the top of the hoist frame is a horizontal supporting plate 9 on which is mounted a motor 10, and this motor is preferably arranged with its power shaft 11 arranged parallel with the drum axes. Keyed to one end of the motor power shaft 11 is a motor pinion 12 meshing with a large spur gear 13 journaled on a bearing sleeve 14 supported by a cross shaft 15, herein arranged parallel with the drum driving shaft 7 and likewise journaled within roller bearings 16, 16 supported within the sides of the hoist frame. Keyed to and driven by the shaft 15 and located at the opposite side of the hoist frame from the spur gear 13 is a spur gear 17 meshing with a spur gear 18 keyed to a cross shaft 19, herein arranged parallel with and below the shaft 15 and likewise journaled within roller bearings 20, 20 supported within the sides of the hoist frame. Keyed to and driven by the shaft 19 is a spur gear 21 meshing with a spur gear 22 keyed to a cross shaft 23, herein arranged parallel with the cross shafts 15 and 19 and likewise journaled within the sides of the hoist frame. Keyed to and driven by the shaft 23 and arranged at the opposite end thereof from the gear 22 at the opposite side of the hoisting mechanism is a spur gear 24 meshing with a large spur gear 25 keyed to the drum drive shaft 7 for the hoisting drums 3, 3. The drums 4, 4 are likewise driven from the motor 10 through gearing including a gear 26 meshing with and driven by the spur gear 13, the gear 26 driving the drum through spur gearing 27, 28, 29, 30, 31 and 32, the spur gear 32 being fixed to the drum driving shaft. The gears 13 and 26 of the drum driving means are connected with their aligned shafts by sliding jaw clutches 33 splined to the shafts. From the foregoing, it will be evident that when the jaw clutches are connected, the pairs of drums may be driven in cable winding direction from the motor 10 through the spur gearing. As the drives for both pairs of drums are substantially the same, a description of the braking means, roller clutch and drum ratchet means for the one pair of drums 3, 3 will suffice for both.

As shown in Figs. 4 and 6, keyed to an elongation 34 of the shaft 15 is a hub 35 of a roller clutch, generally designated 36, of a conventional design, this clutch commonly known as a "free-wheeling" or one-way slip clutch. Secured to this hub 35 is an annulus 37 having cam or wedge surfaces 38 engageable by gripping rollers 39, and these wedging surfaces, upon rotation of the annulus 37 in one direction, effect movement of the rollers into frictional gripping engagement with an internal cylindrical surface 40 formed on an outer annulus 41. This annulus 41 is secured to the hub portions 42, 42 of a brake drum 43, and these drum hubs are journaled in ball bearings supported by the roller clutch hub 35, in the manner shown in Fig. 4. When the annulus 37 is rotated in the opposite direction, the wedging surfaces move into a position to effect release of the gripping rollers from engagement with the cylindrical surface 40 of the outer annulus 41. Engaging the braking surface 44 of the brake drum is a contractible brake band 45 having its ends attached at 46 and 47 to a bell crank plate 48 keyed to an operating shaft 49. Fixed to the operating shaft 49 at the outer side of the hoist frame is a lever 50 having mounted thereon an adjustable weight 51, and this weighted lever acts automatically to effect application of the brake

band frictionally to resist rotation of the drum in cable unwinding direction. It is accordingly evident that when the shaft 15 is rotated in one direction, the "free-wheeling" clutch automatically effects connection of the brake drum with the shaft 15, so that rotation of the hoisting drums in unwinding direction is automatically braked, and when the shaft 15 rotates in the opposite direction, the "free-wheeling" clutch automatically disconnects the shaft from the brake drum, so that the hoisting drums are free to rotate in cable winding direction.

The clutch 33 is provided with a usual clutch shipper yoke 53 engaging a peripheral groove 54 on the clutch, and this shipper yoke is connected to an operating rod 55 guided for axial movement on the machine frame and having at the exterior of the machine frame an operating handle 56. When the operating handle 56 is in the position shown in Fig. 1, with the jaw clutch 33 connected, it overlies the weighted lever 50 of the brake applying means, so that when the clutch 33 is engaged the brake is always applied. When the handle 56 is moved outwardly to effect disconnection of the jaw clutch 33, the weighted lever 50 of the brake may be manually swung upwardly to effect brake release. It will thus be seen that the handle 56 of the jaw clutch operating means provides an interlock, so that whenever the jaw clutch is connected, the brake is always applied. When the handle 56 is moved into its clutch releasing position, the brake lever 50 may be swung upwardly to effect release of the brake. This interlock arrangement insures disconnection of the motor from the drums during lowering of a life boat, and as a result precludes injury to the motor due to an excessive rate of rotation of the motor armature.

A centrifugally operated brake is provided for automatically preventing an excessive rate of drum rotation in cable unwinding direction, and this brake, as shown in Figs. 4 and 7, comprises a pair of swingable brake shoes 60 and 61 engageable, when in expanded position, with the internal cylindrical surface 62 of a stationary brake drum 63 secured to the side of the hoist frame. These brake shoes 60 and 61 are pivotally connected at 64 and 65, respectively, to a member 66 keyed to the shaft 15. The brake shoes are normally urged towards their contracted released position by coil springs 67. It will thus be seen that when the shaft 15 rotates too rapidly in one direction, the brake shoes automatically fly out under the action of centrifugal force into frictional engagement with the cylindrical surface 62 of the stationary brake drum, thereby automatically effecting braking of the shaft and slowing down of the drums.

An automatic dog is provided for permitting drum rotation in one direction relative to the drive shaft 7 while automatically connecting the drums to the drive shaft upon rotation thereof in the opposite direction. This automatic dog comprises an arm 68 having its hub 69 keyed to the shaft 7, and pivotally mounted on this arm at 70 is a dog 71. A spring pressed plunger 72 engages the dog 71 to urge the latter outwardly into engagement with teeth 73 formed on the drum.

Means is provided for rotating the winding drums by hand comprising a sprocket 75 fixed to the drums and connected through an endless chain 76 to a sprocket 77 fixed to an operating shaft 78 suitably journaled within the side of the hoist frame. This shaft has a polygonal portion 79 adapted for the reception of a suitable turn-

ing lever or crank. The drums may also be rotated by hand independently of the motor 10 by placing hand cranks on polygonal projections 80 at the opposite ends of the shaft 15 so that the drums may be manually rotated in cable winding direction through the spur gearing. If desired, the projections 80 may be formed on the motor shaft instead of the shaft 15, in an obvious manner.

When it is desired to launch the life boats, the davits of the launching apparatus are swung outwardly over the side of the ship so that the life boats are suspended over the side of the ship. The operator then grasps the handle 56 and moves the operating rod 55 outwardly to effect release of the jaw clutch 33 from the driving gear 13, the handle 56 moving from its interlocking position above the weighted brake operating lever. The operator may then raise the weighted lever 50 upwardly to effect release of the brake band 45, thereby permitting rotation of the drums in a direction to unwind the cables, and so a lowering of the boats. As the drums rotate in unwinding direction, the dog 71 engaging the teeth on the drums causes rotation therewith of the shaft 7, gearing 25, 24, shaft 23, gearing 22, 21, shaft 19, gearing 18 and 17 and the shaft 15. In the event that the rate of drum rotation becomes excessive, the brake-shoe weights of the automatic brake will fly out under the action of centrifugal force to effect movement thereof into braking relation with the stationary brake drum, and as a result the drums are automatically braked and drum rotation is slowed down to a predetermined maximum speed.

When it is desired to hoist the life boats, the jaw clutch 33 is connected and the motor 10 is operated to rotate the drums through the spur gearing in cable winding direction, the drums being rotated through the spur gearing 12, 13, 17, 18, 21 and 22, 24, 25, the shaft 7 and the automatic dog 71. During rotation of the hoisting drums in cable winding direction, the "free-wheeling" clutch 36 releases automatically to effect disconnection of the brake drum 44 from the shaft 15 so that the brake is automatically disconnected from the drums at that time. When nested life boats are to be launched, the drums may be manually rapidly rotated in cable winding direction between launching of different boats independently of the spur gearing and driving motor 10 through rotation of the shaft 78, and through the chain and sprocket connection 77, 76, 75, the automatic dog 71 slipping over the teeth on the drum at that time. The cable winding drums may be rotated in cable winding direction by means of hand cranks connected to the polygonal projections 80 on the shaft 15 through the spur gearing.

As a result of this invention it will be noted that an improved hoisting mechanism is provided, especially designed for use with a boat launching apparatus, whereby the launching of the life boats may be maintained always under control, resulting in a launching apparatus which is extremely safe in operation, the improved hoisting mechanism having embodied therein safety features which preclude a too rapid lowering of the life boats even when the manual control means is inadvertently entirely released. It will also be noted that instead of the double drum type hoisting mechanism disclosed, wherein pairs of hoisting drums are provided for launching a plurality of boats, if desired only one pair of drums may be employed to effect launching of but a single

boat. It will still further be noted that by the provision of the improved interlock between the drive control clutch and the manually controlled brake, the drive control clutch is always held in released position during release of the brake, thereby preventing possible injury to the driving motor, due to an excessive rate of rotation of the motor armature during the boat launching operation. Other uses and advantages of the improved hoist or winch will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a hoisting mechanism of the character described, a frame, a cable winding drum journaled thereon, a motor on said frame, reduction gearing connecting said motor in driving relation with said drum for rotating the latter in cable winding direction and comprising cooperating speed reducing elements, a clutch for disconnecting certain elements of said reduction gearing from the remaining elements thereof for disconnecting said motor from driving relation with said drum, a brake coaxial with said clutch and connected to said drum through said remaining elements of said reduction gearing for controlling drum rotation in unwinding direction, means for automatically rendering said brake effective only when the drum is rotating in cable unwinding direction, and an interlock between said clutch and brake operative to preclude release of the brake when said clutch is connected.

2. In a hoisting mechanism of the character described, a frame, a cable winding drum journaled thereon, a motor on said frame, reduction gearing connecting said motor in driving relation with said drum for rotating the latter in cable winding direction and comprising cooperating speed reducing elements, a clutch for disconnecting certain elements of said reduction gearing from the remaining elements thereof for disconnecting the motor from driving relation with said drum, a brake coaxial with said clutch and connected to said drum through said remaining elements of said reduction gearing for controlling drum rotation in cable unwinding direction, means for automatically rendering said brake effective only when said drum is rotating in cable unwinding direction, a controlling element for said clutch, and a controlling element for said brake, said clutch controlling element when said clutch is connected precluding movement of said brake controlling element into brake releasing position.

3. In a hoisting mechanism of the character described, a frame, a cable winding drum journaled on said frame, a motor on said frame, driving means between said motor and said drum for rotating the latter in cable winding direction comprising speed reduction gearing, a manually operable clutch in said drive between said motor and said drum for interrupting the drive, a manually releasable, automatic drum brake coaxial with said clutch and having a braking element connected to an element of said driving means and rotating at a different rate from said drum

- during drum drive and automatically braking drum rotation in cable unwinding direction, and a one-way clutch in the drive between said braking element and said drum for rendering said brake inactive during rotation of the drum in cable winding direction by said motor through said gearing, and an interlock between said manually operable clutch and said brake for precluding manual release of said brake when said 10 manually operable clutch is connected.
4. In a hoisting mechanism of the character described, a frame, a cable winding drum journaled on said frame, a motor on said frame, driving means between said motor and said drum for 15 rotating the latter in cable winding direction comprising speed reduction gearing, a drive control clutch embodied in said gearing for disconnecting said motor from driving relation with said drum, a drum brake for braking rotation 20 of the drum in cable unwinding direction, an automatic one-way clutch for rendering said brake ineffective during rotation of said drum in cable winding direction by said motor through said gearing, said motor drive clutch, said brake 25 and said one-way clutch being arranged in coaxial relation, manually operable means for releasing said brake, and an interlock for precluding operation of said brake release means when said drive clutch is connected.
5. In a hoisting mechanism of the character described, a cable winding drum, a motor, driving connections between said motor and said drum for rotating the latter in cable winding direction comprising intermeshing speed reduction 30 gears arranged on parallel axes parallel to the drum axis, an automatic brake coaxial with one of said gears, an automatic one-way slip clutch coaxial with said brake for connecting said brake to said gears to brake rotation of the drum in cable unwinding direction and for automatically disconnecting said brake from said gears when the drum is rotated in cable winding direction, a manually controllable clutch coaxial with said brake and said one-way clutch for disconnecting 35 said motor from said gearing, means for manually releasing said brake, and interlocking mechanism between said manual release means and said manually controllable clutch for precluding brake release when said clutch is connected.
6. In a hoisting mechanism of the character described, a cable winding drum, a motor, driving connections between said motor and said drum for rotating the latter in cable winding direction 40 comprising intermeshing speed reduction gears arranged on parallel axes parallel to the drum axis, an automatic brake coaxial with one of said gears, an automatic one-way slip clutch coaxial with said brake for connecting said brake to said 45 gears to brake rotation of the drum in cable unwinding direction and for automatically disconnecting the brake from the gears when the drum is rotated in cable winding direction, a manually controllable clutch coaxial with said brake and said one-way clutch for disconnecting said motor from said gearing, means for manually releasing 50 said brake, interlocking mechanism between said manual release means and said manually controllable clutch for precluding brake release when said clutch is connected, and a centrifugally controlled automatic brake coaxial with said clutches and said brake and connected to an element of said gearing for automatically preventing an ex-

cessive rate of drum rotation in cable unwinding direction when said manually controllable clutch and said manually releasable brake are released.

7. In a hoisting mechanism of the character described, a cable winding drum, motor operated driving connections for said drum for rotating the latter in cable winding direction, an automatic brake, an automatic one-way slip clutch for connecting said brake to an element of said driving connections for braking drum rotation in cable 10 unwinding direction and for automatically disconnecting said brake from said driving connections when said drum is rotated in cable winding direction, and an automatic one-way clutch between the final element of said driving connections and said drum for permitting free rotation of said drum relative to said driving connections in one direction.

8. In a hoisting mechanism of the character described, the combination of a cable winding drum, a releasable brake for controlling rotation of said drum in cable unwinding direction, said brake having a shiftable operating handle, means for driving said drum in the cable winding direction and including a clutch by which the driving force may be coupled to or uncoupled from the drum, said clutch having a shiftable operating handle, and said brake and clutch operating handles having grasping portions arranged in juxtaposition and providing an interlock between said clutch and brake for preventing release of the brake while said clutch is engaged and operable to permit release of the brake only when said clutch is disengaged and the driving means is uncoupled from the drum, the grasping portion of said shiftable clutch operating handle when said clutch is engaged being disposed in the path of movement of said shiftable brake operating handle so that movement of said brake operating handle into a position to effect release of the 30 brake is at that time prevented by direct engagement of the grasping portion of said brake operating handle with the grasping portion of said clutch operating handle, and the grasping portion of said clutch operating handle when said clutch is released being disposed out of the path of movement of the grasping portion of said brake operating handle to permit movement of the latter into a position to effect release of the brake when the clutch is disengaged.

9. In a hoisting mechanism of the character described, the combination of a cable winding drum, a motor, means operatively connecting said motor in driving relation with said drum for rotating the latter in cable winding direction, a clutch for disconnecting said motor from driving relation with said drum, a brake for controlling drum rotation in cable unwinding direction, means for automatically rendering said brake effective only when said drum is rotating in cable 60 unwinding direction, shiftable operating handles for said clutch and brake respectively, said handles having grasping portions arranged in juxtaposition and the grasping portion of said clutch operating handle when said clutch is connected overlying the grasping portion of said brake operating handle in the path of movement of the latter, thereby to preclude, by direct engagement with the grasping portion of said clutch operating handle, movement of said brake operating handle into brake releasing position.
